CLAIM

I claim the ornamental design for the sanitary hand shield, as shown and described.

DESCRIPTION

FIG. 1 is a top view of the sanitary hand shield.

FIG. 2 is a bottom side view of the claimed design.

FIG. 3 is a side view of the claimed design.

FIG. 4 is a front view of the claimed design; and,

FIG. 5 is a perspective view of the claimed design.

The broken lines shown in FIGS. 1, 2 and 5 represent stitching and form part of the claimed design.

1 Claim, 4 Drawing Sheets(56)
